(57) **CLAIM**

The ornamental design for a LCD screen display, as shown and described.

DESCRIPTION

FIG. 1 is a front view of a LCD screen display; and, FIG. 2 is a perspective view thereof.
In the drawings, the following broken lines are included for the purpose of illustrating environmental subject matter that forms no part of the claimed design: all of the broken lines in FIGS. 1 and 2 that are outside the illustrated circle bound by the solid line.

1 Claim, 2 Drawing Sheets(56)
